UNITED STATES PATENT OFFICE

133,141

DESIGN FOR A BUTTON

Amson Furtsch, New York, N. Y.

Application April 18, 1942, Serial No. 106,611

Term of patent 3½ years

To all whom it may concern:

Be it known that I, Amson Furtsch, a citizen of the United States, residing in the city, county and State of New York, have invented a new, original, and ornamental Design for a Button, of which the following is a specification, reference being had to the accompanying drawing, forming a part thereof, in which:

Fig. 1 is a top plan view of a button showing my new design;

Fig. 2 is a side elevational view thereof; and

Fig. 3 is a vertical cross-sectional view more fully illustrating the embellishment of the rim.

The button is of a flat disk type having a circular raised rim around the edge thereof. The rim is formed with undulations and is provided with transverse striations on the upper surface.

I claim:

The ornamental design for a button, as shown and described.

AMSON FURTSCH.
